UNITED STATES PATENT OFFICE

CLIFFORD SKLAREK, OF CHICAGO, ILLINOIS, ASSIGNOR TO INTERNATIONAL SPOTLIGHT CORPORATION, OF CHICAGO, ILLINOIS, A CORPORATION OF ILLINOIS

DIRIGIBLE SPOTLIGHT

Application filed February 13, 1928, Serial No. 253,820. Renewed September 17, 1931.

This invention relates to dirigible spotlights.

An object of the invention is to provide a universally mounted dirigible lamp, having mechanism for operating the same, including novel gear elements which facilitate smooth and efficient manipulation of the spotlight.

Another object of the invention is to provide operating mechanism for the spotlight, wherein electric conductors are utilized which are carried by the movable parts of the operating mechanism and so arranged as to prevent any possibility of the same being broken or twisted, and which are so disposed as to permit ready assembling and disassembling of the spotlight when desired, without the necessity of "fishing" wires through the parts of the operating mechanism.

Still another object of the invention is to provide a spotlight of a character adapted to extend through the windshield structure of a closed type of automobile, and wherein supporting means for the spotlight are utilized which may be readily adapted to supporting posts of various sizes and contours, and which includes a ball and socket arrangement permitting application of the spotlight structure at different angles to the supporting post, together with a bracket of bendable material which may be bent to form so as to be secured to the supporting post in any desired position.

Other and further objects of the invention will more clearly appear from the description and claims hereinafter following.

In the drawings forming part of this specification, Figure 1 is a side elevational view of the spotlight, the front and rear portions of which, and the supporting post to which the spotlight is connected, being shown in vertical longitudinal section, and the lamp head being partly broken away to expose the interior thereof. Figure 2 illustrates respectively a perspective view of an operating gear associated with an operating shaft of the spotlight and a perspective view of the cooperating gear associated with the lamp head of the spotlight. Figure 3 is a

transverse vertical sectional view through the forward portion of the lamp, corresponding substantially to the line 3-3 of Figure 1. Figure 4 is a transverse vertical sectional view through the rear portion of the operating mechanism, corresponding substantially to the line 4-4 of Figure 1. Figure 5 is a horizontal sectional view through the rear end of the lamp, corresponding substantially to the line 5-5 of Figure 1.

Figure 6 is an enlarged fragmentary, vertical sectional view of the spotlight, showing the supporting means therefor. Figure 7 is an enlarged fragmentary horizontal detailed sectional view through the lamp head gear and showing the same in mesh with the related gear of the driving shaft. Figure 8 is an enlarged fragmentary vertical sectional view through the lamp head gear and showing the same in engagement with the related gear upon the driving shaft.

As shown in the drawings, the spotlight is adapted to be applied to the corner post of the windshield structure of a closed car, said corner post being indicated in the drawings by the reference character 6. In order to mount the spotlight it is necessary to provide an aperture extending transversely through the post 6 at any suitable angle desired, an aperture 7 being indicated in the drawings. To the outer face of the post 6, in proper position with reference to the aperture 7, is secured a supporting bracket 8. The bracket 8 is preferably elongated in form and has its outer marginal edges strengthened by means of a pressed corrugation 9, inwardly of which are provided a number of openings in the bracket to permit the passage of holding screws 10, which are utilized to secure the bracket to the post 6.

Centrally of the bracket 8 is provided an outwardly extending truncated ball-shaped member 11, having a central opening 12. Co-operating with the bracket 8 is the lamp-carrying member 13, which is in the form of a tubular member, having a flared portion 14, the inner surface of which is globular to co-operate with the ball-shaped portion 11 of the bracket, there being provided within the flared portion an annular flange

15, which provides a shoulder to co-operate with a part presently referred to. The member 13 is provided with a hollow tubular extension 16, which extends rearwardly 5 through the opening 7 in the post 6 a suitable distance, and forms with the lamp-carrying member 13 an outer shaft adapted to rotate about its longitudinal axis upon the ball-shaped member 11. A threaded annular portion 160 is formed upon the extension 16 adjacent the ball-shaped member 11, and threaded upon the portion 160 is a ball-shaped part 161, which fits the inner surface 10 of the ball-shaped member 11, the member 15 161 being provided with an annular groove 162 which may be filled with a felt washer, which bears upon the inner surface of the ball-shaped member 11. The extension 16 is provided at the rear of the post 6 with 20 a holding bracket 17, said bracket having bendable prongs 18—18 adapted to be secured to the post 6 by means of screws 19. The bracket 17 is provided with a sleevelike portion 20, which is split to provide a pair 25 of ears, indicated at 21, which fit about the extension 16 and are secured together by means of a bolt 22, which may be tightened or loosened as desired, to thereby vary the frictional contact of the sleevelike portion 30 upon extension 16. The sleevelike portion 20 is provided with an arcuate extension 23, adapted to co-operate with lugs 24 at opposite sides of the collar 25. The collar 25 is clamped to the extension 16 by means of a 35 bolt 26, the lugs 24 being adapted to co-operate with the arcuate portion 23 to limit the turning movement of the extension 16, and further to hold the extension 16 against forward longitudinal movement.

40 The lamp-carrying member 13 and the extension 16 are rigidly secured together by a driving fit as indicated at 29, and the two form the outer shaft which is provided with a central bore 27, in which is rotatably 45 mounted a shaft 28. The forward end of the shaft 28 is provided with a gear made up in the form of an annular enlargement 30, which fits in a counterbored socket 31 of the lamp-carrying member 13, a coiled 50 spring 32 being interposed between the member 30 and the shoulder 33, provided by the bottom of the socket 31. The annular member 30 is provided with an annular series of teeth along its forward edge, indicated 55 by the reference character 34. The teeth 34 are of peculiar formation, being defined by a series of cut-out portions 35, the opposite defining walls 340 of which are straight and disposed parallel to each other, and parallel 60 to radial lines projected from the longitudinal axis of the shaft 28. The bottom of each cut-out portion is curved, as indicated at 36. The teeth 34, so defined by the cut-out portions, have their opposite sides undercut, as 65 best shown in Figures 2 and 3, and said teeth

are of a character to co-operate with a gear connected to the lamp head, as hereinafter described. Disposed within the base portions of the teeth 34 at the end of the shaft 28 is a central annular portion 37, which 70 projects beyond the forward edges of the teeth 34 to form a thrust bearing.

Co-operating with the gear 30 is a gear 38, which rotates about an axis disposed at right angles to the axis of rotation of the 75 shaft 28. The gear 38 comprises a journal portion 39, provided at its lower edge with an annular flange 40 against which the central projection 37 on the gear 30 bears, and outwardly of the flange 40 of the 80 gear 38 is provided with gear teeth 41, adapted to mesh with the gear teeth 34 of the gear member 30. As best shown in Figures 2, 7 and 8, the teeth 41 of the gear 38 are of peculiar formation so as to co-operate 85 with the teeth 34 in a peculiar and efficient manner, whereby great ease and smoothness of operation are obtained. The teeth 41 are each formed as a segment of a ball at its engaging surface. The curved surfaces 410 90 are adapted to be presented for engagement with the flat walls 340 of the gear 30 during the horizontal approach and recession of said surfaces longitudinally with reference to the shaft 28, as best shown in Figure 7, 95 while the curved surfaces 411 are simultaneously presented to the gear teeth 34 to take care of the movement of the teeth 34 in their vertical plane of movement, as shown in Figure 8. In other words, the 100 teeth 34 and 41 travel relatively to each other in two planes and the curved surfaces 410 of the teeth 41 provide a rolling engagement between the teeth 34 and 41 in a 105 horizontal plane, while the surfaces 411 provide a similar rolling engagement in a vertical plane, the surfaces 410 and 411 merging to provide a ball effect so that the ball surfaces roll upon the flat walls 340 in two 110 directions, producing great smoothness of operation and efficiency in action. For this way tight running gears are provided without lost motion between the teeth thereof, the flange 40 bearing upon the annular projecting portion 37 in such manner as to 115 maintain a predetermined clearance for the teeth and eliminate bottoming of the teeth, which ordinarily results in the teeth bumping over each other during rotation of the 120 gears. The journal portion 39 of the gear 38 is rotatably mounted in a nut 42 threaded into the chamber 43 of the lamp-carrying element 13, which nut is provided with an annular channel 44, in which is mounted a coiled spring 45 which bears downwardly 125 upon an annular shoulder 46, formed upon the gear 38. The journal portion 39 of the gear 38 is provided with a reduced annular portion 47, over which fits a washer 48. The lamp head is provided with a portion 49 130

which rests upon the washer 48, and the reduced portion 47 of the gear projects through the portion 49 of the base of the lamp. The portion 37 is still further reduced and threaded for the reception of a nut 50 threaded thereon, between which and the adjacent surface of the portion 49 of the lamp is interposed a washer 51, the arrangement being such that the lamp head is maintained in position and rotates with the journal portion 39 of the gear 38.

The outer shaft provided by the extension 16 and lamp-carrying member 13, at its rear end, carries a handle support 52, which is in the form of a casting having split sleeve-like member 53 at its forward end, which fits over the end of the extension 16 and is rigidly detachably clamped thereon by means of a bolt 54. The handle support 52 is provided with an annular flange 55, in which is rotatably mounted the journal portion 56 of a gear 57. The journal portion is provided with a flange 58, which bears against the flange 55 of the support. The handle proper, indicated at 59 rests against the undersurface of the flange 58, and the handle 59 is provided with a central hollow sleeve 60, extending therethrough, adapted for the reception of a screw bolt 61 which is threaded into the gear 57. The gear 57 is provided with an extension 62, having a reduced portion 63 extending through the wall 64 of the handle support, which reduced portion is internally threaded for the reception of a set screw 65, the head of which bears upon a flanged friction-generating element 66, the latter being provided with a sleeve portion which rests against the shoulder provided by the extension 62. By this arrangement too free rotation of the gear 57 is prevented. The handle support is provided with a socket 68, in which is mounted the journal portion 69 of a gear 70, which meshes with the gear 57, the gear 70 having a central polygonal opening adapted for the reception of the end 71 of the shaft 28, which is polygonal in section to fit the opening in the gear 70, whereby the gear 70 and shaft 28 rotate in unison.

The electrical connections include a conductor 72, extending from a suitable source of supply to a switch block 73 of any suitable character. The switch block 73 is preferably supported by a cup-shaped member 74, detachably connected to the rear end of the handle support 52 by means of set screws 75. The switch 73 is adapted to be operated by means of a lever 76, which projects through the rear wall of the cup-shaped member 74. Connected to the switch block is a resilient conducting member 77, which extends forwardly past the extension 66 of the gear 57 and is coiled about the same, as indicated at 78, and provided with a reversely turned end portion 79, which resiliently

bears upon the rear end of a conducting rod 80. The conducting rod 80 is rigidly mounted in the shaft 28 so as to rotate therewith, and extends entirely through said shaft to a position where it projects from the forward end thereof, as indicated at 81, the portion 81 being annular in form. Co-operating with the portion 81 of the conductor 80 is a conductor 82, carried by the journal portion 39 of the gear 38. Conductor portion 82 is provided with a plunger section 83, slidably disposed within a flange member 84 driven into the lower end of a thimble 85, fitting within a block of insulating material 86, disposed in the central chamber 87 of the journal portion 39 of the gear. The plunger section 83 of the conductor is provided with a flange 88, adapted to limit downward movement of the conductor 82, and interposed between the upper surface of the flange portion 88 and the bottom of the thimble 85 is a coiled spring 90. The thimble 85 is connected to a wire 91 which extends upwardly through the annular portion 47 of the gear 38 and the threaded portion thereof and the nut 50, to the base of the lamp bulb, indicated at 92, thereby completing one pole of the circuit, the remaining pole being suitably grounded upon the lamp structure, and the circuit completed to the battery of the car by means of the wire 93.

In operation, when it is desired to swing the outer shaft, composed of the extension 16 and lamp-carrying member 13, about its axis so as to impart swinging movement to the lamp head, the handle 59 is grasped by the hand of the operator and oscillated to and fro, without rotation about its individual axis. The movement of the outer shaft is limited by reason of the stop lugs coming into engagement with the portion 23 upon the bracket 17. Too free rotation of the extension 16 is regulated by the clamping ears 21 on the sleeve-like portion of the bracket 17.

When it is desired to rotate the lamp head about its vertical axis, the handle 59 is rotated about its individual axis, imparting rotation to the gear 57, the gear 70, the shaft 28, the gear 30, the gear 38, and thence through said gear to the lamp head. Of course, it will be appreciated that rotation, both about the horizontal and vertical axes, may be effected simultaneously, if desired, by one hand of the operator, through combined swinging movement of the outer shaft and rotation of the handle on its individual axis, which effects rotation of the shaft 28. The supply of electricity to the lamp is controlled through the switch lever 76, which may be manipulated through the fingers of the same hand of the operator which is utilized to impart the required movements to the lamp head. The electric circuit is effected by reason of the fact that the resilient

conductor 77 continuously bears upon the rear end of the conductor 80, which in turn rotates with the shaft 28 and bears against the conductor 82 which, through the thimble 85 and wire 91, conduct the current to the base of the lamp bulb, the other pole of the circuit being grounded on the lamp structure.

The lamp-carrying member 13 and extension 16 may be disposed of any desired angle with reference to the post 6, by reason of the universal connection of the flared portion 14 of the lamp-carrying member with the ball-shaped element 11, as will be understood, the bendable prongs 18 of the bracket 17 being bent to whatever position is necessary, whereby they may be secured in proper relation with respect to the opposite side of the post 6. In any position in which the outer shaft, comprising the lamp-carrying member 13 and extension 16, may be mounted, it is afforded free rotation upon the ball-shaped member 11.

The lamp, as thus provided, may be conveniently assembled and disassembled during application, or for purposes of repair, and assuming that it is desired to disassemble the lamp from its position as shown in Figure 1 it is only necessary to loosen the bolt 54, remove the handle support 52, and the collar 25, after which the forward portion of the lamp, including the lamp-carrying member and extension 16, may be moved forwardly and completely removed from the mounting, it being noted that the gear 70 slips off of the polygonal end 71 of the shaft 28 during this movement. The reverse operation, of course, takes place when the lamp is being applied to position. It is particularly pointed out that the electrical connections are susceptible of disassembly with the parts above referred to, without the necessity for fishing wires through the shafts, or other awkward procedure. Access is provided to the switch through removal of the cap-shaped member 74, carrying with it the resilient conductor 77. Due to the provision of the particular type of gears provided between the lamp head and the forward end 50 of the shaft 28, the gears are held in tight engagement so that no lost motion occurs, and the teeth thereof mesh in such manner that the same do not bump over each other. Particular attention is also called to the fact that the conductor 80 rotates with the shaft 28, while the conductor 82 is carried by the journal for the lamp head in resilient contact therewith, whereby any amount of rotation of the lamp head, with respect to the lamp-carrying member 13, will have no effect in interfering with the operation of the conducting means and does away with any possibility of kinking or breaking of wires, so common in other types of lamps.

While I have herein shown and described

what I consider the preferred manner of carrying out the invention, the same is merely illustrative, and I contemplate all changes and modifications which come within the scope of the claims appended hereto.

I claim:—

1. In a device of the character described, the combination with a lamp movable about axes disposed at an angle to each other; of operating mechanism for moving said lamp about its respective axes and including a rotatable shaft carrying a conductor disposed lengthwise thereof and a journal member rotatable about an axis at substantially right angles to the axes of said shaft and provided with an axially disposed conductor, said conductors being relatively rotatable, the conductor in said shaft and said axial conductor extending in line with each other, one of said conductors having a cylindrical contact surface, and the other conductor having the terminal portion thereof bearing upon said cylindrical contact surface; and driving connections between said shaft and journal member.

2. In a device of the character described, the combination with a lamp movable about axes disposed at an angle to each other; of operating mechanism for moving said lamp about its respective axes and including a rotatable shaft carrying a conductor; and a journal member rotatable about an axis at substantially right angles to the axis of said shaft and provided with an axially disposed conductor, the conductor in said shaft and said axial conductor extending in line with each other and bearing one upon the other; a gear carried by said shaft and a gear carried by said journal member and disposed in meshing relation, one of said gears being provided with teeth having surfaces rounded in a direction toward and from said shaft and in a direction substantially at right angles thereto and the other gear having teeth cooperating therewith.

3. In a device of the character described, the combination with a lamp movable about axes disposed at an angle to each other; of operating mechanism for moving said lamp about its respective axes and including a rotatable shaft carrying a conductor and a journal member rotatable about an axis at substantially right angles to the axis of said shaft and provided with an axially disposed conductor, the conductor in said shaft and said axial conductor extending in line with each other and bearing one upon the other; a gear carried by said shaft and a gear carried by said journal member and disposed in meshing relation, one of said gears being provided with teeth having surfaces rounded in a direction conforming substantially to the longitudinal axis of said shaft and also in a direction substantially at right angles thereto; means for urging

said gears toward each other; and thrust bearings for maintaining the teeth of said gears in predetermined meshing relation, said conductors extending axially through 5 and beyond said gears.

4. In a device of the character described, the combination with a lamp movable about two axes; of operating means for said lamp, including an operating shaft member and a 10 journal member rotatable substantially at right angles to each other; driving gears operatively connecting said members; a conductor carried by and rotatable with said shaft member; and a conductor carried by 15 and rotatable with said journal member, the conductor mounted on one of said members having a cylindrical contact surface and the conductor mounted in the other member being yieldingly held in engagement with said 20 cylindrical contact surface.

5. In a spotlight of the character described, the combination with a support; of an outer shaft on said support mounted for rotation about its axis; an inner shaft rotatable about the axis of said outer shaft; a lamp operatively connected with said shafts; a handle support rigidly, but detachably, fixed to the rear end of said outer shaft, said handle support carrying a gear 25 provided with a noncircular opening for the reception of the noncircular end of said inner shaft; a handle extending at an angle to said handle support on said outer shaft and having a gear connected thereto, meshing with the gear on said inner shaft, the handle gear having an integral portion thereof extending through said support, and friction means cooperating with said portion and engaging said support exteriorly to frictionally resist rotation of said handle gear. 35

6. In a device of the character described, the combination with a lamp; of means for operating said lamp, including an outer and inner shaft; a handle support connected to 40 said outer shaft; and a handle member extending at an angle to said handle support and through the latter; means for holding said handle assembled with said support, including a securing member fixed to the 45 handle and holding the same against endwise movement, said securing member having a portion overlying the handle support; friction brake means interposed between said overlying portion and the adjacent section 50 of the handle support; and means connecting said handle with said inner shaft.

7. In a device of the character described, the combination with a support; of a lamp; operating means for said lamp, including a 55 rotary shaft extending through said support; and universally adjustable means for mounting said shaft on said support, including a ball-shaped bracket and bearing members rotatable with said shaft, providing 60 globular surfaces rotatably engaging in-

ner and outer surfaces of said ball-shaped bracket.

8. In a device of the character described, the combination with a support; of a lamp; operating means for said lamp, including a 70 rotary shaft extending through said support; means for adjustably mounting said shaft on said support, including a ball-shaped bracket on said support, and rotatable bearing members on said shaft having globular surfaces engaging inner and outer surfaces of said ball-shaped bracket, said bracket being disposed at one side of said support; and means at the opposite side of said support comprising a sleevelike member for rotatably supporting said shaft, said sleevelike member being provided with bendable prongs adapted to be secured to said support. 75

9. In a device of the character described, the combination with a support; of a lamp; means for operating said lamp, including a rotary shaft extending through said support; means at one side of said support providing a universally adjustable connection of said shaft with said support including a bracket having interior and exterior spherical surfaces and a cooperating holding means on the shaft and rotatable therewith having two spherical surfaces embracing said interior and exterior surfaces; and means at the opposite side of said support, having bendable arms adapted to be secured to said support, and having means for rotatably supporting said shaft. 80

10. In a device of the character described, the combination with a lamp movable about axes disposed at an angle to each other; of operating mechanism for said lamp, including inner and outer shafts; a handle support rigidly secured to said outer shaft; a handle member extending at an angle to said handle support and operatively connected to said inner shaft; a journal member mounted to rotate at a angle to the axis of rotation of said inner shaft; gears connected to said inner shaft and said journal member, one of said gears having teeth provided with ball-shaped surfaces, and the other gear provided with plane-engaging surfaces; and means yieldingly urging said gears into mesh including thrust bearings cooperating with said gears to maintain the teeth thereof in predetermined engagement. 100

11. In a device of the character described, the combination with a lamp movable about axes disposed at an angle to each other; of operating mechanism for said lamp, including inner and outer shafts; a handle support rigidly secured to said outer shaft; a handle member extending at an angle to said handle support and operatively connected to said inner shaft; a journal member mounted to rotate at an angle to the axis of rotation of said inner shaft; gears connected to said inner shaft and said journal 110 115 120 125 130

- member, one of said gears having ball-shaped teeth and the other of said gears having plane surfaced teeth tightly engaged with said ball-shaped teeth; means normally urging said gears into mesh; thrust bearings co-operating with said gears to maintain the teeth thereof in predetermined engagement; a conductor carried by said inner shaft, and a conductor carried by said journal member, said conductors being arranged to bear one upon the other; and means carried by said journal member normally urging the conductor carried thereby into engagement with the conductor carried by said shaft.
12. In a device of the character described, the combination with a lamp movable about axes disposed at an angle to each other; of operating mechanism for said lamp, including inner and outer shafts; a handle support rigidly secured to said outer shaft; a handle member extending at an angle to said handle support and operatively connected to said inner shaft; a journal member mounted to rotate at an angle to the axis of rotation of said inner shaft; gears connected to said inner shaft and said journal member, one of said gears having ball-shaped teeth and the other of said gears having plane surfaced teeth tightly engaged with said ball-shaped teeth; means normally urging said gears into mesh; thrust bearings cooperating with said gears to maintain the teeth thereof in predetermined engagement; a conductor carried by said inner shaft, and a conductor carried by said journal member, said conductors being arranged to bear one upon the other; means carried by said journal member normally urging the conductor carried thereby into engagement with the conductor carried by said shaft; and a switch block carried by said handle support and having a resilient contact member bearing upon the contact member carried by said inner shaft.
13. In a device of the character described, the combination with a spotlight provided with rotatable shafts; of means for supporting said shafts for rotative and tiltable movement with reference to a fixed structure, said means including an element provided with interior and exterior spherical surfaces said means being adapted to be affixed to a fixed structure and cooperating elements carried by said shafts, and rotatable with one of the same having spherical surfaces engageable respectively with the interior and exterior spherical surfaces of said first elements.
14. In a device of the character described, the combination with a support; of a lamp; operating means for said lamp including a rotatable shaft extending through the supporting structure; and adjustable means for carrying said shaft, including a bracket secured to said supporting structure, said

bracket having spherical interior and exterior surfaces, and cooperating holding means carried by said shaft and rotatable therewith, including elements provided with spherical surfaces embracing said interior and exterior spherical surfaces, the element having the spherical surface cooperating with said interior spherical surface being adjustable toward and away from said other element.

15. In a device of the character described, the combination with a spotlight provided with rotatable shafts; of means carrying said rotatable shafts, said means including a bracket fixed to a support and a cooperating holding member, said bracket having interior and exterior spherical supporting surfaces, and said holding member having inner and outer elements rotatable with one of said shafts, said elements being provided with spherical surfaces embracing said inner and outer spherical surfaces, the inner element being adjustably supported on said shafts for movement toward and away from the outer element.

16. In a device of the character described, the combination with a rotary shaft supporting a lamp carrying member, said lamp carrying member being bodily movable with said rotary shaft and rotatable on said shaft about an axis at an angle to the axis of rotation of said shaft; a rotary operating element for said lamp carrying member, said operating element being rotatably supported within said shaft and extending lengthwise thereof; intermeshing gears secured respectively to said member and element, one of said gears having teeth provided with flat engaging surfaces, the flat engaging surfaces of adjacent teeth being disposed substantially parallel to each other and the cooperating gear having teeth having end portions adapted to engage between said parallel surfaces of the teeth of the first named gear, the extremities of said teeth being rounded and closely interfitting with the teeth of the second named gear without lost motion.

17. In a device of the character described, the combination with a lamp carrying element; of means for rotating said element about two axes angularly disposed with respect to each other including inner and outer rotatable shafts; a handle support fixed to one end of the outer shaft; a gear fixed to the corresponding end of the inner shaft and disposed within the handle support, said handle support having opposed walls; means for rotating said inner shaft with respect to the outer shaft including an operating handle carrying a gear member supported for rotation in said handle by means journaled in said opposed spaced walls about an axis at right angles to the axis of rotation of said first named gear member and mesh-

ing therewith; a switch mounted in said handle support at the outer end thereof; a conductor extending axially through said inner shaft; and a connector between the 5 switch and the conductor and having contact with the latter, said connector embracing one of said journal members and being held in position thereby.

18. In a device of the character described, 10 the combination with a lamp carrying member rotatable about two different axes; of means for actuating said lamp carrying member to rotate the same about respective axes including an inner and an outer shaft 15 relatively rotatable with respect to each other; a handle housing fixed to the outer shaft at one end thereof; a gear fixed to the corresponding end of the inner shaft and disposed within said housing; an operating 20 member extending transversely through said housing and journaled in opposite walls of the housing for rotation about an axis at an angle to the axis of rotation of the outer shaft, said operating member including a 25 coaxial handle portion projecting from said housing and a fixed gear member rotatable therewith and meshing with the gear of said inner shaft; a conductor extending through said inner shaft and having a terminal member 30 at the handle end of the shaft; a switch mounted in the housing; and a connecting member between said switch and the conductor, said connecting member being supported by said operating member and having 35 bearing engagement with the terminal member.

19. In a device of the character described, the combination with a lamp carrying member rotatable about two axes at an angle to 40 each other; of means for rotating said lamp carrying member about said axes respectively, including inner and outer rotatable shafts; a handle supporting housing at one end of the outer shaft and fixed with respect to the 45 same; a bevel gear fixed to the corresponding end of the inner shaft; a contact member at the last named end of said inner shaft and a conductor extending through said shaft and electrically connected to the contact 50 member; a switch mounted at the outer end of the handle housing; a transversely disposed operating member extending through said housing, said operating member including a bevel gear portion meshing with said 55 first named bevel gear, a journal portion coaxial with said gear portion at one side thereof, and a handle portion at the other side of said gear portion projecting from 60 said housing, said journal portion having the outer end thereof journaled in a wall of said handle supporting housing; and a detachable connector between said switch and the contact member, said detachable connector having a loop portion partly embrac- 65

ing the journal portion of said operating member and supported thereby.

20. In a dirigible light, the combination with a lamp-carrying member adapted to be rotated bodily about one axis, said member 70 having a threaded opening extending therefrom at an angle to said axis; of a threaded bearing block detachably secured in said opening; a driven gear journaled in said block, said gear having a shank extended 75 outwardly through the bearing block and threaded at its outer end; a lamp casing apertured to receive said extended shank; a nut on said threaded outer end of the gear shank within the casing detachably and 80 rigidly uniting said lamp casing and extended gear shank whereby the same are rotatable in unison and the lamp casing, block and driven gear may be applied or removed as a unit by unscrewing the block from said 85 threaded opening; and means for driving said gear to effect rotation of said lamp casing with respect to the lamp-carrying member.

21. In a dirigible light, the combination with a lamp-carrying member adapted to be rotated bodily about one axis, said member having an opening extending therefrom at an angle to said axis; of a detachable block 90 secured in said opening, said block having an axle journal bearing and an outer bearing seat; a driven gear journaled in said block, said gear having a shank journaled in and extended outwardly through said block; a lamp casing; means rigidly uniting said 95 lamp casing and extended gear shank, said means including a washer engaging said bearing seat and rotatable thereon when the casing and gear are rotated; expandible spring means interposed between said gear and bearing block adapted to compensate, 100 axially, for wear on said washer and seat; and means for driving said gear to effect rotation of said lamp casing with respect to the lamp-carrying member. 105

In witness that I claim the foregoing I have hereunto subscribed my name this 9th day of February 1928.
